UNITED STATES PATENT OFFICE.

ALVIN G. SHERMAN, OF DETROIT, MICHIGAN, ASSIGNOR TO DETROIT VAPOR STOVE COMPANY, OF DETROIT, MICHIGAN, A CORPORATION OF MICHIGAN.

DESIGN FOR A GRATE FOR GAS OR VAPOR STOVES.

Application filed July 15, 1922. Serial No. 3,100. Term of patent 14 years.

To all whom it may concern:

Be it known that I, ALVIN G. SHERMAN, a citizen of the United States, residing at Detroit, in the county of Wayne and State of Michigan, have invented a new, ornamental, and original Design for Grates for Gas or Vapor Stoves, of which the following is a specification, reference being had to the accompanying drawing, forming part thereof.

Fig. 1 is a top elevation of the grate embodying my new design.

Fig. 2 is a side elevation of the same.

I claim:

The ornamental design for a grate for gas or vapor stoves as shown.

ALVIN G. SHERMAN.
